A. P. WEBER

CUTTING TORCH

Original Filed March 15, 1920

UNITED STATES PATENT OFFICE.

ALBERT P. WEBER, OF OVERBROOK BOROUGH, PENNSYLVANIA.

CUTTING TORCH.

Application filed March 15, 1920, Serial No. 365,995. Renewed May 22, 1926.

This invention relates to cutting torches and particularly to torches employing oxygen and acetylene as agents of combustion, and has for an object the production of a simple and highly efficient cutting torch which offers no manufacturing difficulties, and which may be readily assembled and adjusted.

Another object is to produce a cutting torch wherein back firing is eliminated and wherein high pressure fluids are prevented from entering the passages containing fluids of lower pressure.

Another object is to produce a torch wherein the nozzles may be quickly and readily exchanged or replaced without danger of injury to the main casing of the torch.

A further object is to produce a cutting torch wherein the expansion of the metals incident to the heating of the nozzle tends to tighten the connections between the nozzle and the casing.

Another object is to produce a cutting torch wherein the high pressure nozzle and the nozzle for the lower pressure fluids are independently secured to the casing and wherein the connections may be separately and independently adjusted.

These and other objects are attained by means of a cutting torch embodying the features herein described and illustrated in the drawings accompanying and forming a part hereof, wherein:

Fig. 1 is a longitudinal section through the improved cutting torch.

Fig. 2 is a transverse section on the line II—II of Fig. 1, viewed in the direction toward the rear of the torch.

Fig. 3 is a transverse section on the line II—II of Fig. 1 in the direction toward the front of the torch.

Fig. 4 is a transverse section on the line IV—IV of Fig. 1.

Referring to the drawings, the torch includes a casing 5 having a centrally disposed longitudinal bore 6 extending therethrough, adapted to receive the high pressure nozzle 7, which projects from the casing proper and terminates in a nozzle tip 8. The nozzle 7 is provided interiorly with a longitudinally extending passage 9 which communicates with a high pressure oxygen inlet 10 leading into the casing through the threaded cap nut 11. The rear end of the bore 6 expands into a chamber 12 having a conical ground

seat 13 adapted to receive the conical enlargement 14 of the nozzle and form a fluid-tight connection between the casing and the rear end of the nozzle. The rear end of the nozzle is faced and ground at 15 and tightly contacts with a similarly ground opposing face on the cap nut 11 adapted to form a fluid-tight joint between the nozzle 7 and the cap nut, when the said nut is tightly screwed upon the casing 5.

The pipe 16 for supplying the high pressure oxygen terminates in an enlarged conical head 17 which fits into a conical seat 18 provided in the rear end of the cap nut. The head is secured to the ground seat by 70 the union sleeve 19 and may be readily released when it is desired to tighten or loosen the cap nut 11.

The casing is provided with a low pressure oxygen inlet 20 which communicates with the low pressure oxygen supply pipe 21, and with a fuel or acetylene inlet 22 which communicates with the acetylene supply pipe 23.

The nozzle 7 is provided, as shown, with 80 four minute longitudinally extending grooves 24 which communicate at their rear ends with an annular low pressure oxygen receiving chamber 25 formed in the bore 6 and communicating with the low pressure oxygen inlet 20. The grooves 24 form passages between the casing 5 and the nozzle 7 through which low pressure oxygen is conducted forwardly from the receiving recess or chamber 25.

As shown, the forward end of the casing proper is provided with an annular groove 26 which serves as a small storage reservoir for acetylene gas which is supplied thereto from the fuel inlet 22 through three minute 95 passages 27 drilled from the front of the groove into inlet 22. The reservoir 26 is closed by a sealing seat 28 having an annular ridge 29 adapted to snugly fit into the annular reservoir 26 and seal it so as to prevent the escape of acetylene gas therefrom. The surfaces of the sealing seat and the end of the casing are ground so that a fluid-tight joint is obtained by pressing the seat 28 against the casing.

A low pressure or secondary nozzle 30 is snugly fitted over the projecting end of the high pressure or interior nozzle 7 and is provided with a flange 31 at its rear end having a ground face 32 adapted to abut the ground face 33 on the sealing seat 28. The

nozzle 30 is securely clamped against the sealing seat 28, and the said seat is securely held against the casing 5 by means of a threaded nut 28' which is screwed upon the casing 5. The faces 32 and 33 of the nozzle 30 and the seat 28, respectively, are beveled around the central bore thereof and form an annular fuel distributing chamber 34 surrounding the exterior surface of the nozzle 7, which is in communication with the longitudinal grooves 24 in the nozzle 7. The forward ends of the groove 24 are enlarged slightly from a point within the distributing chamber 34 to the tip of the nozzle 7 in order to accommodate the additional gas which is supplied to the grooves at this point from the distributing chamber which receives fuel from the acetylene gas reservoir 26 through a series of minute passages 35 drilled through the sealing seat 28.

When the nut 28' is tightened, the ground faces of nozzle 30, the sealing seat, and the front end of the casing are pressed tightly together and prevent the escape around the joint of low pressure oxygen or acetylene gas from the various passages. I have found that when the casing 5, sealing seat 28 and nut 28' are made of brass, and the nozzle 30 made of copper, which has a higher coefficient of expansion than brass, that the nut 28' may be tightened by hand and that when the nozzle 30 is heated by the operation of the torch, the copper expands and sufficiently tightens the joint without necessitating the use of a wrench. I have also found that the nut may be removed or loosened by hand when the nozzle has been cooled. Nozzles constructed in this manner may, therefore, be readily changed within brief periods of time, and there is no necessity for straining the various parts of the torch, as is frequently done in tightening other forms of nozzles.

It will be seen from the foregoing that high pressure oxygen is supplied to the tip of the nozzle through the passage 9, and that low pressure oxygen is supplied to the tip of the nozzle through the grooves 24, while acetylene gas is supplied to the said grooves and is discharged with the low pressure oxygen. The delivery of fluid through the tubes 16, 21 and 23 is controlled by valves, not shown, which may be adjusted to deliver the fluid at any desired pressure.

To operate the improved torch, the valve controlling the delivery of acetylene gas is opened and adjusted to deliver the gas to the torch, at approximately fifteen pounds per square inch above atmospheric pressure. This gas passes from the inlet 22 through the passages 24 into the reservoir 26, and after passing through the wire gauze screen 36 provided in the reservoir, to prevent back-firing, is conducted to the distributing chamber 34 through the passages 35 from whence

it flows through the enlarged portion of the grooves 24 to the tip of the nozzle where it is ignited. After the acetylene gas has been ignited, the intensity of combustion is increased by supplying low pressure oxygen to the acetylene gas before it is discharged from the nozzle, and this low pressure oxygen is supplied from the oxygen inlet 20 through the chamber 25 and grooves 24 which discharge into the distributing chamber 34. Because of the highly inflammable nature of the gaseous mixture, it is necessary to guard against back-firing. In certain torches now commonly in use, the facilities for preventing back-firing are inadequate, and the result is that explosions occur with such intensity of heat and pressure as to burst the casings of the torch and frequently fuse the parts together and close the fluid passages. When the explosions are not of such violence as to cause physical injury to the torch, they interrupt the flow of gases to the nozzle and cause spluttering which extinguishes the flame. This is very objectionable for the reason that the flame is at this time being used to heat the work preparatory to the cutting operation, wherein the high pressure oxygen is used alone. Interruptions, caused by back-firing, reduce the heating efficiency of the torch and consequently more time is required for this operation than when the flame is even and uninterrupted.

In order to prevent back-firing, I employ relatively long passages having minute cross-sectional areas for conducting the gases to the nozzles. For instance, the passages 24, the number of which varies with the nature of the gases employed, are relatively long, longer than it would be practicable to drill a fine hole through solid metal. To provide such passages, I have, therefore, cut grooves on the surface of the high pressure nozzles which are surrounded by the casing 5, sealing seat 28, and secondary nozzle 30, which parts, while separate, form in effect a casing or housing for the nozzle.

As a further precaution against back-firing, the areas of the ducts 35 leading from the distributing chamber through the sealing seat 28 to the reservoir 26, are reduced to an absolute minimum, and a gauze screen 36 of fine mesh is interposed between these ducts and the minute ducts 27 connecting the acetylene gas intake 22 with the reservoir 26.

During the normal heating operation, wherein a mixture of acetylene gas and oxygen is discharged from the nozzles, there would be little danger of oxygen getting back into the acetylene reservoir because the pressure of the acetylene gas therein would more than balance that in the distributing chamber. However, after the work has become sufficiently heated that it will

sustain combustion when supplied with high pressure oxygen, the acetylene gas and low pressure oxygen controlling valves are closed and high pressure oxygen is supplied to the 5 nozzle through the passage 9. It is apparent that there will remain in the reservoir 26 and inlet 22 a quantity of acetylene gas which might be made inflammable should oxygen be forced back into the reservoir. 10 Precaution is, therefore, made to prevent the leakage of high pressure oxygen into the conduits 24 or to the distributing chamber. The nozzle 7 is, therefore, provided with a ground joint connection, previously described, which is secured to the casing independently of the means for securing the nozzle or tip 30 to the casing and there is, therefore, no danger of loosening this joint when it is desired to exchange or adjust the 15 tip 30.

In many forms of cutting torches, the high pressure nozzle connection serves to connect the cutting tip with the casing and becomes loosened when the tip is replaced, 20 with the result that high pressure oxygen leaks into the fuel chamber and an explosion follows. The provision of an independent connection for the high pressure oxygen conduit and nozzle reduces the possibility for leakage. Should leakage occur, that would 25 force oxygen into the acetylene pipe 23 and inlet 22, the gas in the inlet 22 is amply protected against ignition by the fine ducts 35, screen 36 and ducts 27.

30 After the cutting operation, the high pressure oxygen controlling valve is closed and the torch may again be lighted, preliminary to starting a heating operation, as previously described.

40 The sealing seat 28 and the nozzle 30 might be formed in one piece, but the advantages incident to the construction illustrated resides in the fact that the two piece construction facilitates the manufacture of 45 the parts, and protects the casing 5 from injury when the nozzle 30 is adjusted in position. The sealing seat is applied to the casing 5 and may be renewed without serious loss, should repeated adjustment of the 50 nozzle 30 deface the seat, whereas, if the nozzle were frequently applied to the casing and the seat became injured, repair would necessitate the replacing of an entire new casing instead of a cheaper and more easily 55 replaced sealing seat.

The construction above described is simple and relatively compact compared with the usual torches now employed, and the parts may be readily manufactured and assembled. While I have described the torch 60 as being operated with acetylene as a fuel, other fuels may be employed, and the passages designed and proportioned to accommodate other fuels without departing from 65 the spirit of my invention.

While I have described and illustrated but one embodiment of my invention, it will be apparent to those skilled in the art that various changes, modifications, substitutions, additions and omissions may be made in the 70 apparatus without departing from the spirit and scope of the invention as set forth by the appended claims.

I claim as my invention:

1. A cutting torch comprising a casing, a 75 detachable nozzle extending through the casing provided with a fluid passage extending longitudinally of the nozzle, means for supplying fluid under pressure to the said passage, means for connecting the said means to the nozzle and for securing the nozzle to the casing so as to prevent leakage of fluid from the said passage into the casing, a secondary nozzle adapted to receive fluid under pressure from a passage in the casing 80 communicating with the exterior of the first nozzle, and means for securing the secondary nozzle to the said casing.

2. A cutting torch comprising a casing having a high pressure fluid inlet, a low 90 pressure fluid inlet, and a fluid inlet, a high pressure fluid nozzle extending through the casing, having an interior passage communicating with the said high pressure fluid inlet, and having longitudinal grooves in its 95 exterior surface communicating with the low pressure fluid inlet through which low pressure fluid is conducted to the tip of the nozzle, and means for discharging fluid fuel into the said grooves from the said fluid 100 fuel inlet at a point intermediate the fluid inlet and the discharge ends of the grooves.

3. A cutting torch comprising a casing having a high pressure fluid inlet, a low 105 pressure fluid inlet, and a fluid fuel inlet, 110 a nozzle having an interior passage in communication with the high pressure fluid inlet, and a plurality of relatively small passages communicating with the low pressure 115 fluid inlet, a chamber within the casing receiving fuel from the fluid fuel inlet through a plurality of relatively small passages 120 adapted to prevent back-firing therethrough, and means for connecting the said chamber with the said small passages for the low pressure fluid, whereby fluid fuel is mixed with low pressure fluid within the said passages for low pressure fluid.

4. A cutting torch comprising a casing having a longitudinal bore therethrough, and a high pressure fluid inlet, a low pressure fluid inlet and a fluid fuel inlet, a high pressure nozzle extending through the bore and having an interior passage for high pressure fluid communicating with the high pressure fluid inlet, and a groove in the exterior of the nozzle communicating with the low pressure fluid inlet, an annular groove 125 in the casing forming a chamber for receiving fluid fuel from the fluid fuel inlet 130

through minute orifices adapted to prevent back-firing, and means for connecting the said chamber with the groove for low pressure fluid.

5. A cutting torch comprising a casing having a longitudinal bore therethrough, and a high pressure fluid inlet, a low pressure fluid inlet and a fluid fuel inlet, a high pressure nozzle extending through the bore in the casing and projecting from one end of the casing, and having a high pressure fluid passage communicating with the high pressure inlet, and a groove in the exterior surface thereof communicating with the low pressure fluid inlet, a secondary nozzle surrounding the projecting end of the high pressure nozzle, provided with a fluid fuel distributing chamber communicating with the fluid fuel inlet and with the said groove in the high pressure nozzle, the said high pressure nozzle having a groove in its exterior surface leading from the said fuel distributing chamber to the tip of the nozzle, forming a passage between the secondary nozzle and the high pressure nozzle having a greater area than the groove connecting the low pressure inlet with the fuel distributing chamber.

6. A cutting torch comprising a casing having a longitudinal bore and provided with a high pressure fluid inlet, a low pressure fluid inlet, and a fluid fuel inlet, a high pressure nozzle extending through the longitudinal bore, having an interior high pressure passage communicating with the high pressure fluid inlet, the said nozzle and cas-

ing being so constructed as to provide a passage therebetween for low pressure fluid from the low pressure inlet to the tip of the nozzle, and a fuel reservoir within the casing receiving fuel from the fluid fuel inlet and provided with outlet passages communicating with the said low pressure passage at a point intermediate the low pressure fluid inlet and the tip of the nozzle.

7. A cutting torch comprising a casing having a longitudinal bore and provided with a high pressure fluid inlet, a low pressure fluid inlet communicating with the said bore and a fluid fuel inlet, a high pressure nozzle extending through the bore and having a high pressure fluid passage extending therethrough communicating with the high pressure inlet, means for adjustably holding the nozzle in assembled relation with the casing and for closing communication between the said bore and the said high pressure passage, a secondary nozzle surrounding the said high pressure nozzle cooperating with the said high pressure nozzle to form a discharge passage therebetween communicating with the said bore and receiving fluid fuel from the said fluid fuel inlet, and means for adjustably attaching the said secondary nozzle to the casing and for closing communication between the said bore and the exterior of the casing except through the said discharge passage.

In testimony whereof, I have hereunto subscribed my name this 6th day of March, 1920.

ALBERT P. WEBER.
